SINGLE PULSE RELAY

Kurt Schlesinger, West Lafayette, Ind., assignor
to Radio Corporation of America, a corporation
of Delaware

Application July 30, 1942, Serial No. 452,922

5 Claims. (Cl. 250—27)

1

This invention is related in general to relaying and switching forms of vacuum tube apparatus. In general, the invention set forth is directed to ways and means by which electronic apparatus may be triggered, so to speak, under the control of energizing impulses, and by which provision may be made so that the time period of the triggering or switching operation may be readily controlled.

In the past, it has been known to provide switching or triggering apparatus of the general type known in the art as locking circuits which embodied direct connection by way of resistors or the like between the electrode elements included within two independent thermionic discharge paths which might be embodied in either one or a plurality of vacuum tubes.

Such forms of apparatus essentially provide for a triggering or switching action which took place under the influence of a control signal, and in which the newly assumed state of the apparatus continued until some other form of control signal of opposite polarity arrived to change the state of the operation.

Other forms of apparatus, known in the art as multi-vibrators, which were provided, generally speaking, by the so-called A. C. cross connections between the plate and grid elements of a plurality of independent thermionic discharge paths formed in one or two vacuum tube envelopes provided for a switching between two extreme conditions with the time period of switching and interruption being governed in accordance with a pre-selected time constant of circuit operation, the time constant having been set by the values of the capacity and resistance elements forming the cross connecting circuits. Such forms of multi-vibrators might be of the usual type, or they might even be provided by the so-called cathode coupled type.

The present invention is, in its circuit structural features, somewhat in the nature of a system embodying a direct connection between the output of one thermionic discharge path and the input of a second independent or separate thermionic discharge path and an A. C. or resistance-capacity connection between the output of the second thermionic discharge path and the input of the first thermionic discharge path.

Under these circumstances, a signal impulse arriving upon the system changes its state of operation from one form to another, and the modified operation is maintained for a period which is determined by the time constant of the circuit feeding back energy from the second

2

thermionic discharge path to the initially controlled thermionic discharge path. At the end of this time period, the system is so constituted that it will return to an initial state and remain that way indefinitely until a new controlling pulse of suitable polarity is applied. Upon the receipt of such a pulse, the system will then perform one cycle of operation. Pulses of opposite polarity which arrive at approximately the end of the natural period synchronize the setting of the relay, but pulses arriving too soon after the start of the operational cycle are completely without effect upon the system.

The apparatus, as it will herein be explained, also might be defined as somewhat in the nature of an over-coupled regenerative system in that it is amplitude limited and triggers in either an "on" or an "off" position. The feedback path between the second thermionic discharge path and the first thermionic discharge path has a predetermined low frequency limit so that it cannot transmit direct currents but is able to transmit alternating current down to a predetermined low frequency limit. Thus considered, the connection between the output of the second thermionic discharge path and the input of the first thermionic discharge path is essentially in the form of a high-pass filter arrangement which ceases to transmit feedback energy after a period corresponding to its low frequency limit. Then, the relay falls back into a sort of standby condition. The normal plate or anode output energy from the second thermionic discharge path is, in a sense, distorted, while the cathode output from this same thermionic discharge path is distorted in the opposite direction. This invention provides for combining the two outputs and, by suitably adjusting the tapping point at which the combined output is derived, a truly square wave output may be obtained with but slight expense of signal output.

Accordingly the invention has, as one of its primary objects, that of providing thermionic apparatus which may be operated under the control of suitable signalling energy, and which, when so controlled, will develop truly square wave energy output and will operate through one cycle of adjustable time duration for each controlling signal impressed upon the system.

A further object of the invention is that of providing a suitable relay means which is capable of adjustment to provide for an output pulse of any desired time duration which, for instance, may be that corresponding to the time of receipt of a plurality of signal pulses of which those other

than the initial controlling pulse pass by without in any way affecting the setting or operation of the relay.

A further object of the invention is to provide a system for triggering controlled apparatus accurately under the control of energizing signal impulses by means of suitable coupling which results in a differentiation of the input energy versus time curve.

Other objects of the invention are to overcome one or more known defects of the prior art forms of switching arrangements, such, for instance, as those used to obtain flat-topped output from distorted square waves. At the same time there is provided a relatively simple and foolproof form of relaying device which can readily be manufactured and placed in operation.

Other objects and advantages will become apparent from a reading of the following specification in connection with the accompanying drawings, of which,

Fig. 1 is a schematic form of circuit arrangement showing one form of the apparatus, and

Fig. 2 is constituted by a series of curves for illustrating the preferred form of circuit operation.

Referring now to the drawings, and first to Fig. 1, it will be seen that the form of relay apparatus herein disclosed is essentially of the general type set forth as a part of my United States patent entitled "Synchronizing Signal Generator," which was granted June 6, 1944 as No. 2,350,536.

In its preferred form, the invention has been illustrated, as in the co-pending application referred to, as embodied within a single thermionic tube having a plurality of independent discharge paths. However, it is, of course, apparent, from the outset, that a plurality of separate tubes may be used equally as well. In the disclosed form of the invention, signal energy impulses from a source (not shown) are applied to a terminal input point 21 and fed through a high-pass capacity coupling 23 to the control electrode or grid 25 of the first thermionic discharge path of a vacuum tube 27, which discharge path is embodied between the cathode 29 and the anode 31. This electron flow is controlled by the signal energy applied to the control electrode 25 to vary its potential relative to the cathode.

The other thermionic discharge path is embodied between the cathode 29', the control electrode or grid 33 and the plate or anode 35. A connection, in the form of a bleeder or leak resistor 37, is provided between the control electrode 25 and the cathode 29, and the cathodes 29 and 29' are connected to ground 39 by way of the biasing resistor 41. Under some conditions, the resistor 41 may be replaced by a battery or other source of potential serving as a biasing element, or may be shunted for all but very low frequencies by an electrolytic condenser. In any event, the distributed capacity across the resistor or other appropriate bias source 41 is conventionally represented by the capacity 43. Signal output energy from the first thermionic path, as derived from the plate or anode 31 of the tube 27, is then supplied by way of the coupling resistor 45 to the control electrode or grid 33 in the second thermionic discharge path, and this grid or control electrode 33 is, in turn, connected to ground 39 by way of the leak or bleeder resistor 47.

To feed back energy from the second thermionic discharge path, as it appears at the plate or anode element 35 of the tube 27, a connection is provided by way of the condenser 49 and the bleeder resis-

tor 51 to the grid or control electrode 25 of the first thermionic discharge path, so that under one condition it is apparent that there is a direct current connection between the first thermionic discharge path to supply the energy as it appears at the plate or anode 31 to the control electrode 33 of the second thermionic discharge path, and there is a connection by way of the alternating current coupling provided by the condenser 49 and resistor 51 to feed back energy from the second thermionic discharge path as it appears at the plate or anode 35 to energize the control electrode or grid 25.

Suitable anode potential for the two thermionic discharge paths is provided by way of the battery or other potential source 53 connected between ground 39 and the plate or anode elements 31 and 35, with the resistors 57 and 55 connected respectively in the leads to the anode elements 31 and 35.

To derive output energy from the system as herein disclosed, connections are made by way of the resistors 59 and 61, connected respectively to the plate or anode 31 and to the cathode 29, and having their common point connected to an output terminal 67, and also a second connection for deriving output energy is provided by way of the resistors 63 and 65 connecting, in turn, to the anode or plate 35 and the cathode 29' with the common point or junction of the two resistors connected to a second output terminal 69.

The output energy thus derived is conventionally represented by the curves of Fig. 2, where the curve *d* represents the output at the terminal point 67 for a controlled impulse applied to the control electrode 25 from the terminal 21, and the curve *e* represents the output at the terminal point 69 under like conditions.

In considering the operation of the system hereinabove described, it will be apparent from what has been described that this system operates in such a manner as to develop only a single output pulse at any time, and the duration of the output pulse so derived is determined readily by an arrangement of the time constant of the system which is based upon the value of the capacity 49 and the combination of the resistors 51 and 37 serving to function together as bleeder resistors in the feedback combination. So considered, it will be apparent that the time constant of the feedback circuit is equal to the product of the value of the capacity 49 times the sum of the values of the resistors 51 and 37 and 55.

Accordingly, in considering the operation of this system, it may be assumed that if any triggering impulse is applied to the terminal point 21 that the system will stand by, or operate in such a state that the left portion of the tube 27, that is, the portion embodied by the cathode 29, control electrode 25 and the plate or anode 31, is conducting, in which event the second half of the tube 27 will be blocked because the control electrode 25 is connected to the cathode 29' across the resistor 37, and consequently, any resultant output energy will be non-commutative.

The system, however, may be triggered to a different state of operation by an impulse of negative polarity applied to the terminal input point 21, and thus transferred to the control electrode or grid 25 of the tube 27, and provided the system had a time constant shorter than the interval between two successive input pulses of the same polarity, it would tend to trigger on the next positive pulse applied to the terminal input point 21 to resume its original state of operation,

but, by virtue of the selection of the time constant provided by the selected values of the capacity 49 and the resistors 51 and 37, this time can be varied over a substantially reasonably wide range so that the system may be made to trigger after the arrival of a selected plurality of opposite control pulses of predetermined spaced time duration applied at the input terminal 21.

Considering the system further, the cathode and complete outputs of the relay device hereinabove described are represented by the curves *a*, *b* and *c* of Fig. 2, with the plate output from the first half of the tube, that is, at the plate or anode 31, being represented for instance by the curve *a*, and the plate output at the second half of the tube, for instance at the plate or anode 35, being represented by curve *c*, curve *b* representing the cathode output which it will be seen is distorted in the opposite sense from that of the plate outputs, as is the case with the unblocked cathode resistor 41 shown.

Since the output terminals 67 and 69 respectively derive the combined output from the plate and cathode elements of each of the halves of the tube 27, it can be seen that the output of the first half of the tube at the anode and at the cathode may be mixed in the common resistive network formed from the resistors 59 and 61, and similarly, that the output of the second half of the tube can be mixed in the combined resistive output provided by the resistors 63 and 65.

In any case, it is apparent that in actual practice the resistors 59 and 61 or 63 and 65 may be in the nature of a potentiometer with the connection of the terminal points 67 and 69 respectively being determined by suitable adjustment of the tapping point, so that the output derived at the terminals 67 or 69 shall be for terminal 67, the difference between curves *a* and *b* as will be represented, for instance, by curve *d* which is an output pulse of positive polarity, and for terminal 69 will be represented by the difference between the curves *c* and *b*, which, for instance, is represented by the curve *e* of Fig. 2 and is of negative polarity for an applied negative pulse at the input or control terminal 21.

With a suitable choice of values for the resistors and the capacity and a source of operating voltage 53 chosen as of the order of about 200 volts, it is apparent that an output voltage of the order of about 50 volts may readily be derived at the terminal points 67 and 69, it of course being apparent that the square wave output obtainable at the terminal points 67 and 69 is derived somewhat at the expense of amplitude because of the necessity of obtaining the difference signal from the cathode and the plate outputs, all as indicated by curves *d* and *e* of Fig. 2.

It will be noted, from the circuit arrangement shown, that controlling pulses may be applied to the terminal 21 and through the condenser 23 to the control electrode or grid 25. Under these circumstances, the controlling pulse, as it arrives at the terminal 21, is of negative polarity. However, as also indicated by the drawings, the system may be triggered or operated by a controlling pulse of positive polarity, which signal pulse will be applied to the terminal point 21a and fed through a condenser 23a to the control electrode or grid 33 of the second half of the tube or the second thermionic discharge path.

In this connection, the input coupling to each of the systems is somewhat important, in that it will be apparent that the system hereinabove described is so constituted that it will respond to any

decrease in bias upon the control electrode or grid 25, so that the control electrode is carried negative to its previous state, and likewise the system will respond to any increase in bias applied to the control electrode or grid 33 by which this electrode member is carried positive relative to its previous state.

The relay device then starts to perform a single cycle or pulse of operation of predetermined duration. If, for instance, it is intended to transform an input pulse of arbitrary wave form into a square wave of equal duration, the time constant of the relay is adjusted to match the signal period, after which two forms of input coupling are possible, which can be characterized as, first, amplitude coupling, and, second, pulse coupling.

Under the condition of amplitude coupling, the condensers 23 or 23a are made large, or they may be replaced by a suitable biasing battery or other biasing source so that D. C. coupling is provided. Under such conditions, the relay will respond as soon as the impressed signal wave exceeds a critical value, but its start will not quite coincide with the wave zero point, nor will the backkick, because the two levels are not identical.

For the second condition of pulse coupling, the condensers 23 or 23a are made relatively small or substantially equivalent to a high frequency transformer coupling. Now the pulse to provide the control may be derived from an impressed signal where the rate of change is a maximum, so that it will be observed, as a general rule, the second method of pulse coupling leads to more accurate results and, generally speaking, improved timing.

What I claim is:

1. A relay device comprising electronic apparatus wherein is included a plurality of independent anode and cathode elements between which separate electron discharge paths are developed, and a control electrode means for controlling each of the said thermionic discharge paths, means for supplying control signals to the control electrode included in one of the thermionic discharge paths for controlling the electron flow therein, direct current connection means for energizing the second of said thermionic discharge paths under the control of the signals flowing in the first thermionic discharge path, alternating current connection means comprising a time constant circuit including capacity and resistance elements for controlling the energy in the first thermionic discharge path in proportion to the current flowing in the second of said thermionic discharge paths, a pair of resistance elements having one terminal of each connected to the cathode elements included in each thermionic discharge path, a connection from the other terminal of said resistance elements to independent anode elements of each thermionic discharge path, and an output connection to an intermediate point on each of the resistor elements.

2. An electronic relay device comprising thermionic apparatus including means to develop a plurality of independent controllable electronic current paths, means for supplying signals to control the first of the said independent electron current paths, direct current means for controlling the second electron current path in proportion to the current flowing in the first electron current path, regenerative means comprising capacity and resistance elements for controlling the flow of current in the first electron current path also under the influence of the current flowing in the second electron current path, and re-

sistive output means connected to be energized in accordance with each electron current flow, said resistive output means each having one terminal connected to a common point in each of said electron current paths.

3. Electronic apparatus comprising thermionic means having a plurality of electrodes to develop a plurality of independent controllable electronic current paths, means for normally maintaining electron flow in one of the current paths, resistance means connecting said electron current path to the other electron current path for normally interrupting electron flow in the second named path, means for applying controlling impulses to one of the electron current paths to change its state of operation to a condition opposite that normally maintained, alternating current feedback means comprising capacity and resistance elements connecting the second named electron path with the first electron path to provide feedback to the first path so that during periods of electron flow in the second path the first path is de-coupled for time periods at least as great as the time constant provided by the resistance and capacity in the feedback path, resistance means connected to the output of each electron path for deriving output energy in accordance with the current flowing in said path, and compensating resistance means also connected with said first named resistance means and with the electron path for providing substantially undistorted square wave output from each path.

4. Electronic apparatus comprising thermionic means having a plurality of electrodes to develop a plurality of independent controllable electronic current paths, means for normally maintaining an electron flow in the first of the said electronic current paths, resistance means connecting said first electronic current path to the other electronic current path for normally interrupting electron flow in the second named path, means for applying controlling impulses of negative polarity to the first of the electronic current paths to interrupt the flow of current therein, alternating current feedback means comprising capacity and resistance elements connecting the second named electronic path with the first electronic path to provide feedback to the first path so that during periods of electron flow in the second path the first path is de-coupled for time periods at least as great as the time constant provided by the resistance and capacity in the feedback path, a common resistance element connected in each electronic path through which the current flows, output resistance means connected to the output of each electronic path for deriving

output energy in accordance with the current flowing in said path, and a connection to the common resistance means and the output resistance means included in each electron path for introducing a wave form compensating voltage whereby substantially undistorted square wave output energy is derived from each path.

5. Electronic apparatus comprising thermionic means having a pair of separate anode elements and a pair of galvanically connected cathode elements between each of which anode and cathode elements an independently controllable electronic current path is developed, means including a control electrode for normally maintaining the electron flow in the first of the current paths, resistance means connecting said electron current path to the other electron current path to normally interrupt current flow in the said other electron path, coupling means for applying controlling impulses to the first of the electron current path to change its state of operation to a condition opposite that normally maintained; a resistor element connecting the control electrode included in the first electron current path to the common cathode elements, an alternating current feedback means comprising serially connected capacity and resistance elements connecting the anode of the second named electron current path with a control electrode of the first electron current path to provide feedback to the first path so that during periods of electron flow in the second path the first path is decoupled for time periods at least as great as the time constant provided by the resistance and capacity in the feedback path, and resistive output means connected to be energized in accordance with each electron current flow, said resistive outputs each having one terminal connected to a common point in each of said electron current paths.
